3,369,114 AIRFIELD RUNWAY LIGHT FIXTURE EXTENSION

Ben C. Carter, Rte. 3, Box 130, New Bern, N.C. 28560
Filed Oct. 25, 1966, Ser. No. 589,446
12 Claims. (Cl. 240—1.2)

This invention relates to flush-mounted airfield runway light fixtures, sometimes referred to as inset light units of the type having a receptacle or base part and a cover or light-carrying part. More particularly, this invention relates to extensions for use with existing light fixtures to provide a raised mounting for the cover or light-carrying part of the fixture, the extension, being in electrical contact with the existing receptacle or base member, in order to elevate the cover to a raised runway surface such as when the runway is repaved.

Use of flush-mounted airfield runway lights recently has become common. These light receptacles are mounted in a shallow hole in runways, taxiways, aprons and the like made of concrete or other material, so as to be substantially flush with the top surface of the runway. Runways require constant maintenance and are regularly resurfaced, the resurfacing resulting in the raising of the runway surface. It, thus, becomes necessary to alter the existing light installations so that the light is again flush with the paving.

It is an object of this invention to provide for remounting the cover or light-carrying part of the fixture flush by utilizing the existing receptacle and the existing electrical circuitry, thereby to avoid disturbing the pavement and existing wiring that is embedded in epoxy or other similar hard materials.

An other object of this invention is to provide an extension adapted to be mounted directly upon the base part of an existing conventional flush-mounted airfield runway light fixture and which is also adapted to receive on the upper surface thereof the existing cover or light-carrying part of the fixture.

Still another object of this invention is to provide an extension as aforesaid which also provides for electrical continuity between the terminals of the existing receptacle part and connections to the cover part.

Other objects and advantages of the invention will become apparent as the invention is described in connection with the accompanying drawing.

According to this invention, an extension is provided for raising the height of an existing conventional airfield runway light consisting of a receptacle or base part and a cover or light-carrying part, said extension including a duplicate of the base part and an electrically non-conductive body part, the lower surface of which is configured to be the mating image of the upper surface of the existing base part so as to permit mated mounting thereon of the extension whilst the upper surface of the body part is configured to be mating image of the lower surface of the duplicate base part, whereby the original cover can be mounted on the extension flush with the raised runway surface. A pair of insulated apertures is provided through the extension aligned with existing electrical contacts in the existing receptacle to provide passage for means such as metal screws for electrically joining the cover and the original receptacle.

In the drawing:

FIG. 1 is an exploded perspective view of a runway lighting unit according to this invention, showing the cover and receptacle parts with the new extension inbetween them. FIG. 2 is a perspective view of the bottom side of the extension of FIG. 1. FIG. 3 is a fragmentary sectional

2

view of the extension of FIG. 1, the section being along line 3—3 of FIG. 1, mounted on the receptacle part.

Referring to the drawing, a known type of runway centerline light fixture is illustrated in FIG. 1 together with the new extension. The known fixture comprises a circular metallic base member, designated generally by numeral 10, in the form of a flanged disc having a continuous bottom wall 12 and a circular peripheral wall 14, the upper edge of which is offset outwardly forming a shoulder 16 and then upwardly forming rim 18r and downwardly forming skirt 18s. At diametrically opposite positions spaced inwardly from the peripheral wall, two bosses 15, 15' are formed integrally with the base member and rise from the bottom wall 12. These bosses are bored and tapped for the reception of securing screws (not shown).

Also at oppositely, but non-symmetrically spaced positions rising from the bottom wall adjacent the peripheral wall are two more bosses 17, 17' which are bored and tapped to receive terminal screws (not shown). Webs 13 extending from one boss to another and to the peripheral wall 14 may be provided to strengthen the structure. The terminal screws pass through the bosses 17, 17' and thread into small flat terminal plates or nuts 19t (FIG. 3) to which pigtail wire leads 19w are soldered, the wires being led around in an internal groove or channel 18c in the bottom face of the base member to an aperture 18a in the skirt 18s. The terminal plate 19t is insulated from the base member 10 by an insulation plate 10p, and the terminal screw is insulated from the base member by a flanged insulating sleeve 10a.

In the known type of runway lighting unit, a cover member designated generally by numeral 20 is circular and of generally disc-shape and of such dimension that it will fit within the lip 18 and lie on the shoulder 16 of the base member 10. The cover is formed with one or more radial channels 22 depressed into its top surface, flaring outwardly from a lens 24 mounted in the depression near the center of the cover.

The cover has mounted on its inner or under surface a known type of electric lamp and terminals for wire connections (not visible) to the terminal screws that pass through the bosses 17, 17' of the base. Since these details are not, per se, part of this invention, further description and illustration of them are not given, but reference may be made to Patent 3,113,726 for a suitable example.

The cover was originally secured to the base by screw bolts passing through holes 26 in the cover and threading into the tapped bores in the bosses 15, 15' of the base 10.

When a device having the parts above described is originally installed, the cover 20 is flush with the runway surface.

When the runway is resurfaced, the base portion 10 advantageously remains in place, so that repositioning will be avoided and movement of the incoming and outgoing wiring ducts and wire connections will be unnecessary. However, due to the runway surface having been raised by the new pavement, the cover must be raised to the new pavement level.

For that purpose, the present invention provides an extension which is designed and constructed to be placed between the existing base and cover members. The extension is advantageously and economically constructed by taking a duplicate 30 of the base member 10 and molding onto the bottom a solid body 32 whose lower surface is configured to mate exactly with the upwardly facing surface of base 10 in all its configurations, as if the hollow upper portion of the base were itself used as the bottom half of a mold.

The material of which the body 32 is made is preferably a mixture of a synthetic plastic cement and blasting sand.

This mixture is advantageous because it is non-corrosive and is a good electrical insulator. However, the invention is not restricted to this mixture as other mixtures, or metal, may be used. But, if metal is used, then insulating sleeves should be used wherever contact screws pass through the extension.

When the body is molded or cast onto the duplicate base 30 and hardens, the body part 32 and the duplicate base portion 30 permanently merge together inseparably to form a single integral unit. This is the preferable construction. However, the body part can be made separate and caused to adhere together by an adhesive or can be secured together by bolts or other common securing means.

It is possible to put two base portions together and use them as the top and bottom of a mold, with the space between them filled with the mixture, provided of course the top surface of the bottom of the thus-formed mold can be, or is coated so that it can be parted from the resulting molded body. This procedure is only possible when the height of the extension is to equal or exceed the height of two stacked base members 10.

As a result of the molding, mating recesses 31, 33 are provided for the webs and bosses of the base member 10.

The height of the extension may vary, but in all cases in which the cover is to be raised more than the height of the outside peripheral surface of the base member, the peripheral wall of the body will be of the same dimensions and form as the peripheral walls of the base members 10 and 30 so that there is a continuous peripheral side wall of the assembly when the parts are assembled.

While it is preferable for the bottom surface of the body 32 to be a mating counterpart of the upper surface of the member 10, complete counter-identity is not an absolute essential. Substantial counter-identity will suffice. In other words, there may be some voids within the body 32 which are larger than, or are not required by, upstanding protuberances on the base 10. Rim and central support are desirable, and also a continuous exterior wall to keep out dirt and moisture.

When the cover 20 and base 10 were originally installed, terminal screws passed through axial holes in the bosses 17, 17' and threaded into the terminal plates 19, which, as illustrated, are located in recesses in the bottom face of the base 10. The recesses are filled and the terminal plate is covered by wax or other insulating material, as is common in covering exposed parts.

When the extension is put in place, the aforesaid terminal screws are removed and longer terminal screw bolts 36 are substituted as in FIG. 3, passing through aligned screw-bolt passageways 38 in the duplicate base portion 30 and body 32 of the extension. Wire or other connections to the electric light bulb (not visible) in the cover 20 will be made to the substituted terminal screws.

When the body 32 is made of the insulating material as described, or other suitable insulating material, insulation such as tubular sleeves 34 and flanged sleeve 35 is not necessary. But when the body 32 is conductive, such sleeves are needed. In all cases, the flanged sleeve 10g is used.

In use, it is assumed that a conventional fixture consisting of base 10 and cover 20 already exists, flush-mounted in an airfield runway. In order to raise the level of the cover 20 to the raised level of the runway after repaving thereof, the existing base 10 is lightly sandblasted to remove all dirt, varnish, etc., and is then coated with an adhesive material such as an epoxy cement. The extension is then mounted on the existing base 10. The extension can fit only in one orientation on the base 10 because the bosses 15, 15' are non-symmetrically placed.

After the extension is in place, two electrically conductive contact screw-bolts 36 are inserted through the screw hole 34 in the extension and electrically engage the terminal plates 19, in the existing base member 10.

Thus, this invention provides a means for permitting

use of a conventional lighting fixture without disturbing an existing base member and without requiring rewiring since electrical continuity throughout the existing base and the raised and newly mounted cover is insured.

5 The extension is a unit which is easily manufactured, for example by molding as described, and it is easily mounted. Alignment of the extension with the existing base is insured because of the mating match therebetween.

10 Whilst in the specification and drawings a particular electric fixture and a configuration of an extension for use with that fixture is illustrated, the principle of the invention is adaptable to other fixtures having different configurations. Many modifications within the scope of the invention will occur to those skilled in the art. Therefore, the invention is not limited to the details and example shown and described.

What is claimed is:

1. For elevating the upper or flush surface of an existing flush-mounted lighting fixture of the type having base 20 and cover members, an extension comprising a body having a lower surface configured as substantially the mating image of the upper surface of the base member of an existing lighting fixture, said body having an upper 25 surface configured as substantially the mating image of the lower surface of the base member of a second lighting fixture to be mounted thereon, said body including a pair of apertures extending therethrough, at least one of each of said apertures being aligned with an electrical 30 wire terminal provided on said existing first lighting fixture, said lower and upper surfaces of said body being spaced apart a distance equal to the desired elevation of the flush surface of said first existing fixture.

2. An extension as defined in claim 1 wherein said 35 body is formed of an electrically non-conductive and non-corrosive material.

3. An extension as defined in claim 1 including an electrically non-conductive bushing mounted within and traversing the length of at least one of said apertures.

40 4. An extension as claimed in claim 1 which is comprised of said body and the base member of a lighting fixture which are in permanent adherence together, forming a single unit.

5. An extension as claimed in claim 1 which is comprised of the base member of a lighting fixture onto the 45 bottom surface of which said body is molded and permanently adhered, forming a single unit.

6. An extension as claimed in claim 5 in which the adhered base member is a duplicate of the base member on which the extension is to be mounted.

50 7. In combination, a first lighting fixture of the type having cover and base members and having a pair of electrical wire terminals in the base, an extension comprising a body mounted on the base of said first fixture, a second lighting fixture base member similar to the first and mounted on said extension body, said extension body having a lower surface configured as substantially the mating image of the upper surface of said first base member and said body having an upper surface configured as substantially the mating image of the lower surface of said second base member, said lower and upper surfaces of said extension body being spaced apart a distance to elevate said second base member a desired 55 distance above said first base member, said body including a pair of apertures aligned with said electrical wire terminals, and means extending from said second lighting fixture through each of said apertures and electrically connecting with the wire terminal of said first lighting fixture and providing electrical connecting means for wires connecting with said second lighting fixture, said 60 connecting means also securing said first and second base members and said extension body in assembled condition.

75 8. The combination as claimed in claim 7 wherein the connecting means is an electrically conductive screw bolt,

9. The combination as claimed in claim 7 in which the extension body is permanently secured to said second fixture.

10. The combination as claimed in claim 7 in which said extension body is molded on and permanently adhered to the bottom surface of said second base member forming a single unit.

11. The combination as defined in claim 7 wherein said extension body is formed of an electrically non-conductive and non-corrosive material.

12. The combination as defined in claim 7 including an electrically non-conductive bushing mounted within and traversing the length of each of said apertures.
